(57) **CLAIM**

The ornamental design for a combined handle and clip for slow cooker, as shown and described.

DESCRIPTION

FIG. 1 is a perspective view as seen from the top, front and right side of a slow cooker showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a magnified view of a combined handle and clip for slow cooker showing the new design.

The broken lines shown are included for the purpose of illustrating the unclaimed portions of the article that form no part of the claimed design.
